ATTORNEYS

UNITED STATES PATENT OFFICE

WILLIAM KRANZ, JR., OF LITTLE ROCK, ARKANSAS

SUBSOILING ATTACHMENT FOR PLOWS

Application filed April 18, 1931. Serial No. 531,208.

This invention relates to agricultural implements and its general object is to provide an attachment for a plow in the form of a subsoiler that is adjustable to vary the height thereof with respect to the ground, in an easy and expeditious manner and while the plow is in motion if desired.

Another object of the invention is to provide a subsoiler that can be attached to plow beams of various diameters and with very little effort.

A still further object of the invention is to provide a subsoiler of the character set forth, that includes a root cutter mounted for cooperation with the plow of the subsoiler.

Another object of the invention is to provide a subsoiler that is simple in construction, inexpensive to manufacture, and extremely efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a side elevation of the subsoiler which forms the subject matter of the present invention and illustrates the same attached to a plow.

Figure 2 is a view partly in section taken through the mounting for the shank of the subsoiler plow.

Figure 3 is a sectional view taken approximately on line 3—3 of Figure 1, looking in the direction of the arrows.

Figure 4 is a sectional view taken approximately on line 4—4 of Figure 1, looking in the direction of the arrows.

Figure 5 is a detail view illustrating members of the means for attaching the subsoiler to a plow beam.

Figure 6 is a sectional view taken approximately on line 6—6 of Figure 1, looking in the direction of the arrows.

Figure 7 is a sectional view taken approximately on line 7—7 of Figure 1, looking in the direction of the arrows.

Referring to the drawing in detail, the letter A indicates the beam of a plow which is of the usual construction, and the attachment which forms the subject matter of the present invention is secured to the beam as clearly shown in Figure 1.

The attachment which in fact is a subsoiler as has been previously set forth includes a beam 1 that is curved upon itself to provide a vertical portion 2, the latter being hollow for the major portion of its length as at 3, and this hollow portion is provided with an opening arranged in the rear thereof as best shown in Figure 2.

The end of the beam 1 opposite to the hollow portion is pivotally secured to a clamping means which is adapted to secure the subsoiler to the beam A, and this clamping means includes a strip 4 having one end arranged at right angles with respect to the body portion. The right angle bent end of the strip 4 is provided with a threaded opening while the body portion is likewise provided with a threaded opening, the latter being indicated by the reference numeral 5, and the body portion is also provided with an opening 6 that is adapted to register with an opening 7 arranged through the reinforced or enlarged end of a companion strip 8 that is likewise provided with a right angle bent end 9 which is serrated as shown. Arranged at the right angle bent end 9 is a slot adapted to register with the opening of the right angle bent end of the strip 4 and a serrated block 10 cooperates with the right angle bent end 9 for the purpose of receiving a bolt 11 that is provided with a lock nut 12, the bolt 11 being adapted to engage the beam A when the parts are associated therewith as shown in Figure 4, and passing through the openings 6 and 7 is a bolt and nut connection 13 which pivotally secures the beam 1 with respect to the beam A. A bracing member 14 has one end secured to the bolt of the bolt and nut connection 13 and this last mentioned end is provided with an opening through which passes

a bolt 15 that likewise engages the beam for cooperation with the bolt 11.

The opposite end of the bracing member 14 is secured to the ears 16 of a collar 17, the latter surrounding the lower end of the hollow portion of the beam 1 as best shown in Figure 2.

Extending from the beam 1 at the top of the vertical portion thereof is an apertured lug 18 that has pivotally secured thereto the enlarged lower end of an operating member 19 and this operating member includes a shank from which extends a pin 20 arranged in a slot 21 of a handle 22 that has secured thereto a collar 23 for the purpose of receiving the shank as shown in Figure 1. By this construction, it will be apparent that when it is not desired to use the handle, it can be moved to either of its dotted line positions as shown in Figure 1, but when the handle is to be used in a manner which will be presently described, it is arranged in its full line position in Figure 1.

The enlarged portion of the operating member 19 has pivotally secured thereto one of the ends of a link 24, while the opposite end of said link 24 is pivotally secured to a tongue 25 that is formed with the shank 26 of the plow bracket 27 for the plow of the subsoiler.

Extending from the beam 1 is a stud 28 that is adapted to be received in any one of a number of notches 29 which are formed with the vertical portion of a latching member 30 which is also pivotally secured to the tongue 25 as best shown in Figure 6 and the latching member 30 has extending therefrom a lever 31 for the purpose of receiving the foot of the operator of the device. Extending from the bolt and nut connection 13 is an eyed link member 32, while extending from the latching member 30 is a similar eyed link member 33, and these eyed link members 32 and 33 have secured thereto the ends of a coil spring 34 which is adapted to hold one of the notches of the operating member 30 with the stud 28 disposed therein as shown in Figure 1.

The plow of the subsoiler is preferably formed from a single piece of material and the mold board portion thereof which is indicated by the reference numeral 35 is curved transversely upon itself as best shown in Figure 2, and the landside portion of the subsoiler plow has fixed thereto the plow bracket 27 which is provided with a pair of slots and an opening, the latter being adapted to receive a bolt and nut connection 36 whereby the plow is pivotally associated with the bracket 27 and adjustable thereon through the medium of bolt and nut connections 37 passing through the slots of the bracket. This adjustment is accomplished upon movement of a wedge 38 that is received between

the upper end of the mold board and an angle bracket 39 formed with the shank 26.

A root cutting blade 40 has one of its ends secured to the forward end of the subsoiler plow, while its opposite end is secured to a pin 41 which is attached to the shank 26 and extends through a slot formed in the hollow portion of the beam 1 as best shown in Figure 2. The root cutter blade is provided with a sharpening forward edge.

From the above description and disclosure of the drawing, it will be obvious that I have provided a subsoiler that can be easily and expeditiously attached to plow beams of various diameters and the height of the plow of the subsoiler is adjustable vertically. When it is desired to move the plow of the subsoiler the latching member 30 is released from its stud 28, and the handle 22 has arranged in its full line position as shown in Figure 1 whereby it will act upon the operating member 19 for raising and lowering the plow as desired. The latching member 30 can be actuated by the foot of the operator, and the plow of the subsoiler can be adjusted during movement of the plow if such action is necessary or desired.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A subsoiler attachment for plows, comprising a beam curved upon itself to provide a hollow vertical end portion, means for pivotally securing the opposite end portion to a plow beam, said means being adjustable to accommodate plow beams of various diameters, a plow bracket including a shank mounted for vertical movement in the hollow portion, a tongue formed with said shank, an operating member pivotally secured to the subsoiler beam, a link having one of its ends pivotally secured to the operating member and its other end pivoted to the tongue, a pivoted handle for the operating member, means for fixedly associating the handle with respect to the operating member, said operating member being adapted to adjust the plow bracket vertically through the medium of the handle, a foot operated latching means for securing the plow beam in any one of its adjusted positions, a plow adjustably secured to the plow bracket, and a root cutter having connection with the plow.

2. A subsoiler attachment for a plow comprising a beam provided with a hollow portion, means for securing said beam to a plow beam, a plow bracket including a shank mounted for vertical movement in the hollow portion, a hand lever, an operating mem-

- ber pivotally secured to the subsoiler beam and having means pivotally and slidably receiving the hand lever, means for fixedly associating the hand lever to its receiving
6 means, a link having pivotal connection with the shank and pivotally secured to the operating member for adjusting the plow bracket vertically by the handle, latching means for securing the bracket in adjusted positions
10 having pivotal connection with the shank, a vertical portion included in the latching means and having notches along one side thereof, a stud extending from the subsoiler beam and adapted to receive any one of the
15 notches, a foot lever formed integral with the vertical portion, and a plow adjustably secured to the plow bracket.

In testimony whereof I affix my signature.
WILLIAM KRANZ, JR.
